UNITED STATES PATENT OFFICE.

HERVEY S. VASSAR, OF BLOOMFIELD, NEW JERSEY.

REFRIGERATION.

Application filed January 18, 1926. Serial No. 81,891.

This invention relates particularly to refrigeration of the class covered in my Patent 1,570,416 of January 19th, 1926, in which a substantially constant refrigeration temperature is maintained by a dual control system involving separate controllers subjected to conditions at remotely related parts of the system, each effective to interrupt or reduce the refrigerating action and connected in series or tandem relation so as to require their joint or cooperative action to initiate or increase the refrigerating action.

The objects of the present invention primarily are to provide practical applications of the aforesaid dual control to refrigerators of different types and to utilize for the more or less remotely related thermostatic controls, various forms of devices best suited to answer particular requirements.

Various other objects and the novel features of construction, combination, arrangement and relation of parts by which all are attained will be clear from the following specification.

The drawings accompanying and forming part of this specification illustrate the invention embodied in a number of different practical forms, but as these drawings are primarily of an illustrative character, it should be understood that the structure may be modified in various respects without departure from the spirit and scope of the invention.

Figure 1 is a broken diagrammatic view showing a form of the invention applied to a refrigerator of the absorption type, the controls being indicated as electric thermostats, one associated with the cooling element and the other located in the storage compartment and the two of them governing an electromagnetic controlling the supply of gas to the absorption mechanism.

Figure 2 is a view similar to the first showing mechanical controls substituted for the electric controls.

Figure 3 is a view on the order of the preceding illustrating a primary electric system employing electric heating in place of gas and having the tandem controls connected directly in series with the electric heater.

Figure 4 is an enlarged fragmentary detail of the dual sylphon operating mechanism shown in Figure 2.

Figure 5 is an enlarged detail of a dual electromagnetic form of master switch control.

Figure 6 is a diagrammatic view of a dual thermostatic control system showing one of the sylphons controlled from an expansion bulb in the system chamber and the other sylphon controlled by a connection with the pressure side of the refrigerating system.

Figures 7, 8 and 9 are diagrammatic views illustrating how the joint efforts of both sylphons are necessary to initiate the refrigerating action.

In the first three views the invention is illustrated in its application to a system of absorption refrigeration. The refrigerator structure is indicated at 10 defining a food or storage compartment 11 cooled by an absorption machine 12. In the first two views the heat necessary for the operation of this machine is furnished by gas supplied through piping 13 and in the third view the heating element is of the electrical type supplied from the mains 14, 15. The dual control is effected in each instance by thermostatic controls 16, 17, the first associated with the cooling element 18 of the absorption machine and the second located in the storage compartment.

In Figure 1 the thermally governed controls are indicated as sylphon actuated switches 19, 20, the first governed by temperature conditions at or adjacent the cooling element and included in a circuit 21, one side of which is connected with a magnet 22 and the other being governed by temperature conditions in the storage compartment and included in a circuit 23, one side of which is connected by wiring 24 in series with the first circuit 21 and the other side of which is connected by wiring 25 with one of the mains 26. The other side 27 of the mains is shown connected directly with the magnet 22 and this magnet is shown as arranged to actuate the arm 28 of a valve 29 located in the gas supply line. This valve is biased to the closed position by a spring 30 or otherwise and the armature 31 of the magnet is connected with the valve arm so that the magnet when energized will operate to open the gas supply valve, the spring closing or shifting the valve in the closing direction when the magnet is deenergized.

The series connection of the two sylphon

switches 19, 20 requires the closing of both to complete the circuit through the valve magnet 22 and hence the temperatures at the cooling unit and in the storage compartment must have reached the predetermined maximums for which the sylphon switches have been respectively set before the gas valve will be opened to initiate or increase the refrigerating action of the absorption machine. When, however, the temperature at either one of these points has been reduced below the maximum intended at that point, the sylphon at such point will open the switch there and thereby interrupt the circuit through the valve magnet, causing the reduction or discontinuance of the forced refrigeration.

In order that the machine may be operated when necessary independently of conditions in the storage compartment, when, for instance, it may be desired to make ice for table use, an arbitrary control is shown in the form of a manually operable switch 32 connected to bridge the circuit 23 of the food compartment controller. This hand switch is shown located on the outside of the box where it can be reached without disturbing conditions in the box.

In Figure 2 the same general results are obtained by the substitution of mechanical in place of electrical connections. The cooling element and storage compartment controllers 16, 17 are shown in the form of expansion bulbs, the first applied to or mounted closely adjacent the cooling element and the other located at a convenient point in the storage chamber and the two connected by independent piping 33, 34 with sylphons 35, 36 jointly operating the gas supply valve by a mechanical series or tandem connection.

Details of the mechanical series connection are shown more fully in Figure 4 where the two sylphons are indicated as having heads bearing on the opposite ends of a swinging rocker 39 pivoted intermediate its ends at 40 to one end of a link 41 whose opposite end is pivoted at 42 to one end of a lever 43 pivoted at 44 and having a sliding connection at 45 with the arm 28 of the gas supply valve 29.

Considering Figures 4, 7, 8 and 9, it will be seen that the linkage described has the effect of a series or tandem connection between the two thermostatically controlled devices because neither sylphon has a stroke sufficient to operate the valve and one must add its stroke to that of the other to effect an opening of the supply valve.

In the first two views referred to the sylphons are contracted and the gas supply valve is closed, these being the conditions when the temperatures at the cooling unit and the storage compartment are sufficiently low. When, however, the temperature at one of such stations rises above the predetermined maximum decided for that point, the

gas in the expansion bulb, expanding, will operate the sylphon connected therewith. As shown in Figure 8, when the cooling unit sylphon 35 has been brought into action by a rise of temperature at the cooling unit, the effect of this action is to shift the upper end of the rocker 39 but the motion thereby imparted to the valve lever is insufficient to open the valve. When, however, the temperature in the storage chamber rises sufficiently to cause the necessary expansion of gas in the bulb 17, then the second sylphon 36 comes into action and shifting the lower end of the rocker adds sufficient extra movement to the valve lever to open the valve and admit fuel to the absorption machine.

To afford a manual control similar to that first described for ice making purposes and the like, a turn button 46 or the like may be provided, having a finger or cam 47 positioned to operate on the lower end of the rocker and thus to substitute its operation for that of the storage chamber sylphon. This operation is indicated in Figure 9.

Where electric heat is provided for the absorption machine, as indicated in Figure 3, the heater 48 may be connected at one side directly with one of the mains, 15, and at the opposite side by wiring 49 with one of the electric controls, the control 16 at the cooling element, in the illustration, the latter being shown as a thermostatic circuit closer 50 connected by wiring 51 with another thermostatic circuit closer 52, which latter serves as the controller 17 for the food compartment and is connected by wiring 53 with the other side 14 of the line.

The thermostatic switches 50, 52 at the cooling unit and in the storage compartment respectively, being connected in series with each other and with the heater for the absorption machine, it will be obvious that when both these close, due to rises in temperature at these particular points, the heater will be cut into circuit and forced refrigeration thereby started and conversely, that when the temperature at either of these relatively remotely related parts is lowered below the predetermined maximum for that point, the heating element will be cut out of circuit and the refrigerating action be thereby interrupted or reduced.

In Figure 3, as in Figure 1, an external control switch 32 is provided for bypassing the storage compartment control and enabling forcing of the refrigeration for manufacture of cube ice and the like.

What is in effect an electrical equivalent of the dual sylphon structure of Figure 4 is shown in Figure 5. In this view, in place of sylphons 35, 36, directly controlled from expansion bulbs at the cooling element and storage compartment, solenoids 54, 55 are provided connected by wiring 56, 57 with thermostatic switches 58, 59 at the cooling

element and the storage chamber. The movable cores 60, 61 are connected by compensating linkage similar to that shown in Figure 4 and correspondingly numbered, the final 5 lever 43 in this case carrying a tilting switch 62 controlling a circuit 63 which may govern a magnet valve as in Figure 1 or a heater circuit as in Figure 3, or in the case of a compression machine, may control the motor 10 which effects circulation of the refrigerating fluid.

The application of a form of the mechanical control to refrigerating apparatus of the compressor type is illustrated in Figure 6. 15 In such an installation the refrigerating action may be initiated by simply starting the motor 64 which drives the compressor 65, which latter is connected with a condenser 66 from which piping 67 extends through an 20 expansion valve 68 to one end of a coil in the brine tank 69, the opposite end of such coil being connected by return piping 70 to the low pressure side of the compressor. In this 25 particular instance the thermostatic control from the cooling unit or brine tank 69 is effected by piping 71 tapping the return piping 70 of the compressor and connected with a sylphon 72. The storage chamber control comprises an expansion bulb 73 located in 30 the storage compartment and connected by piping 74 with a sylphon 75. The two sylphons 72, 75 are connected by compounding linkage 76, similar to that before described, with the operating handle 77 of a switch 78 in the motor circuit 79. The sylphons in this 35 case are so constructed, arranged or adjusted that with the rise in pressure in the return pipe, resultant from a predetermined increase of temperature at the cooling unit 40 and upon a predetermined rise of temperature in the storage chamber, the two sylphons will combine their efforts by the mechanical series connection illustrated, to close the switch and start the motor. 45 Conversely, with reduction of temperature below the predetermined maximum in either storage chamber or at the cooling unit, which latter would have the effect of reducing the pressure in line 70, one or the other or both 50 the sylphons will contract and allow the spring 80 to open the switch to stop the motor and interrupt circulation of the refrigerating fluid.

From the foregoing it will be apparent that 55 the series effect of the dual thermostatic control may be obtained in various ways and be either purely electrical or purely mechanical, or combinations of electrical and mechanical, mechanical and pressure, etc., to meet different requirements or conditions and that the 60 invention is equally applicable to different refrigeration systems, such for instance, as

either of the well-known types of compression and absorption refrigeration.

It will be apparent furthermore, that these 65 features of interchangeability and adaptability enable application of the invention to other refrigerating needs than those here illustrated so it should be understood that the expressions employed herein are used in a descriptive rather than in a limiting sense, except possibly for such limitations as may be required by the prior art.

What is claimed is:

1. In refrigeration, a machine of the absorption type including a cooling element and a heater for effecting operation of the machine, a conduit for flow of heating fluid to said heater, a control valve in said conduit, actuating means for said valve, a thermostatically governed controller adjacent the cooling unit, a thermostatically governed controller located at a point removed from the cooling unit, means for connecting said controllers with each other and with the valve 80 operating means to require joint operation of both controllers to effect opening movement of the valve and arbitrarily operable means for effecting opening movement of the valve independently of one of the controllers but 90 jointly and in conjunction with the other of the controllers.

2. In combination with a refrigerating machine including a cooling unit and means for governing the operation of the same, a pair 95 of sylphon devices and means whereby the same are independently controlled and compensating linkage from said two sylphon devices requiring the joint operation of both to effect a predetermined operation of the governing means aforesaid.

3. In combination with a refrigerating machine including a cooling unit and means for governing the operation of the same, a pair 105 of sylphon devices, means whereby the same are independently controlled and compensating linkage from said two sylphon devices requiring the joint operation of both to effect a predetermined operation of the governing means aforesaid and means independent of 110 one of the sylphons for imparting to said linkage an equivalent of the movement ordinarily imparted thereto by said sylphon.

4. In refrigeration, a refrigerating machine, including a cooling unit, a control lever therefor, a rocker having a connection with said control lever, dual operating devices connected with said rocker and operable jointly thereon to actuate the control lever and a hand control operable on the rocker in place 120 of one of the dual operating devices.

In witness whereof, I have hereunto set my hand this 15th day of January, 1926.

HERVEY S. VASSAR.
